UNITED STATES PATENT OFFICE.

LESSER BERNHARDT GROESCHEL, OF NEW YORK, N. Y.

SAFETY RECEPTACLE.

Application filed October 6, 1921. Serial No. 505,847.

To all whom it may concern:

Be it known that I, LESSER B. GROESCHEL, a citizen of the United States, and a resident of the city of New York, borough of Manhattan, in the county and State of New York, have invented a new and Improved Safety Receptacle, of which the following is a full, clear, and exact description.

This invention relates to safety receptacles for holding groceries or the like.

Prior to this invention it has been the experience of many that when groceries are delivered and no one is at the residence to receive them they are deposited on the door-step or in some unlocked building or box. The consequence is that before the arrival of the owner they are removed by some unscrupulous individual.

The object of this invention is the provision of a safety receptacle that may be left open for the reception of the groceries or the like and that may be locked and attached to some immovable support after the groceries or the like have been placed therein.

A further object is the provision of a receptacle that may be closed after it has been removed from the support so that the contents may be carried by means of a handle attached to the lid.

These objects are accomplished by providing a box having a hinged lid and means mounted thereon that may be associated with means carried by some support or immovable object and locked thereto by some locking means which serves to retain the receptacle closed and fixed to the support.

These and other objects of the invention will be more clearly understood from the following detailed description and accompanying drawings.

Figure 1 is a perspective view showing the safety receptacle mounted on a door and locked in position;

Figure 2 is a side elevation of the safety receptacle showing the means for connecting it to the door;

Figure 3 is a cross section along the line 3—3, Figure 2; and

Figure 4 is a cross section along the line 4—4, Figure 2.

Referring to the above-mentioned figures, a door 10 is shown on which the safety receptacle may be mounted. The safety receptacle consists of a box 11 having a hinged lid 12. This lid 12 is carried by two hinges 13

and 14. Attached to the edge of the lid 12 by means of rivets 15 is an eye member 16 which extends a short distance beyond the edge of the receptacle. A hook 17 is fixed by means of rivets 18 to the lower portion of the side of the box over which the eye member 16 extends. A socket 19 is mounted on the door 10 and serves to engage the hook 17. Mounted on the door above the socket 19 and located in such a position that they register with the eye member 16 when the hook 17 is engaged in the socket 19 are two eye members 20 and 21. These eye members are shown attached to the door by means of screws 22, but are preferably attached by means of rivets or bolts so that they cannot be removed without great difficulty. A bar 23, provided with a ring 24 and an opening 25, of such a size that it may be projected through the eye members 16, 20 and 21, is provided. The ring 24 is of a sufficient size to prevent the bar being drawn through the eye members, and the opening 25 serves as a means for attaching a lock 26 to prevent the removal of the bar by drawing it in the other direction.

Mounted on the ends of the box are two buckles 27 and 28. Fixed upon the lid of the box are two spring plates 29 and 30. When the receptacle is not mounted upon the door the buckles 27 and 28 may be moved into engagement with the plates thus serving to hold the lid closed. A handle 31 is connected to the lid of the receptacle and serves as a means for carrying it when the lid is held closed by means of the buckles 27 and 28.

A slight modification of the locking means is shown in Figure 2. In this case a head 32 is formed on the end of the bar 23. A spring lock 33 is mounted on the door and has an opening in the side with which the head of the bar 23 registers. This lock 33 is provided with spring engaging means that grip the head 32 of the bar 23 when it is inserted so that the bar may not be removed without the key that fits the lock 33.

When it is desired to use the safety receptacle for the reception of groceries or the like it is detached from the door and left open. Upon the arrival of the delivery man he places the groceries, milk or other commodities in the receptacle, then engages the hook 17 in the socket 19 and projects the bar 23 through the eye members 16, 20 and 21. The spring lock 26 is then locked in position

2
in the opening 25, or, in case of a lock such as shown at 33, forces the head 32 of the bar into the lock. Thus the receptacle is locked shut and in connection with a support or an immovable object.

I would state in conclusion that while the illustrated examples constitute practical embodiments of my invention, I do not limit myself strictly to the exact details herein illustrated since manifestly the same can be considerably varied without departing from the spirit of the invention as defined in the appended claims.

Claims:

15 1. A safety receiving receptacle, comprising a box having a hinged lid, means mounted on the box for engaging with means attached to a support to retain the box in position on said support, rings mounted on the lid and support, a sliding bar for attaching the rings, and means for locking the sliding bar in position in the rings to lock the box closed and to the support.

20 2. A safety receiving receptacle, comprising a box having a hinged lid, a hook mounted on the box, a socket mounted on a door or wall for engaging the hook, an eye member mounted on the lid and associated with a pair of eye members mounted on said door or wall by means of a rod extending through them, and means for locking the rod in position.

25 3. A safety receiving receptacle for mounting on a door or wall, comprising a box having a hinged lid, a socket mounted on the door, a hook attached to the box and shaped to engage the socket, a ring member mounted on the lid and associated with a plurality of ring members mounted on the

door or wall by means of a bar extending 40 through them, a lock mounted on the door or wall for engaging the rod to lock it in position, buckles mounted on the box to engage the lid and retain it closed when the box is not mounted on the wall or door, and 45 means mounted on the lid for carrying the box.

4. A safety receiving receptacle of the class described, comprising a box for mounting on a support, a hinged lid mounted on the box, an eye member mounted on the side of the lid opposite the hinges, and a hook member mounted on the side of the box, a socket for engaging the hook and a plurality of eye members for co-operating 50 with the lid eye member mounted on the support, a rod for extending through the eye members to hold the box in position on the support, and means for locking the rod in position to retain the box closed. 55

5. A safety receiving receptacle of the class described, comprising a box for mounting on a support, a hinged lid in conjunction with the box, a bar-engaging member mounted on the lid, a plurality of bar-engaging members mounted on the support, a hook and socket, one mounted on the support and the other on the box, a bar for attaching the lid bar engaging member to the support bar engaging member to retain 60 the receptacle closed and the hook and socket engaged, a lock mounted on the support for engaging the bar to hold it in position, means in conjunction with the box for retaining the lid closed when removed 65 from the support, and a handle mounted on the lid for carrying purposes. 70 75
